(57) **CLAIM**

The ornamental design for a wall component comprising a booth, as shown and described.

DESCRIPTION

FIG. 1 is a first perspective view of a wall component comprising a booth according to our new design;

FIG. 2 is a second perspective view of the design of FIG. 1 shown rotated relative thereto;

FIG. 3 is a side view of FIG. 2;

FIG. 4 is a side view of FIG. 1;

FIG. 5 is a sectional plan view taken along lines 5-5 of FIG. 3;

FIG. 6 is a sectional plan view taken along lines 6-6 of FIG. 3;

FIG. 7 is a sectional plan view taken along lines 7-7 of FIG. 4; and,

FIG. 8 is a sectional plan view taken along lines 8-8 of FIG. 4. The dash-dot broken lines illustrate environmental structure and form no part of the claimed design.
